UNITED STATES PATENT OFFICE.

SOLOMON F. STEVER, OF FAIRFIELD, IOWA.

RAILWAY-RAIL JOINT.

SPECIFICATION forming part of Letters Patent No. 463,082, dated November 10, 1891.

Application filed December 14, 1889. Serial No. 333,800. (No model.)

To all whom it may concern:

Be it known that I, SOLOMON F. STEVER, a citizen of the United States, residing at Fairfield, in the county of Jefferson and State of Iowa, have invented certain new and useful Improvements in Railway-Rail Joints; and I do hereby declare the following to be a full, clear, and exact description of the invention, such as will enable others skilled in the art to 10 which it appertains to make and use the same.

This invention relates to railway-rail joints.

The object of the invention is to form such a joint that any wearing or loosening of the same, as from cross-wear, may be taken up and 15 the joint at all times be kept tight and firm, making the joint as strong as the main portion of the rail, and thus presenting a practically continuous rail for the track.

With this object in view the invention consists, essentially, in a railway-rail joint comprising, with the ordinary angle-bars, downward and outward inclined jaws to be placed one on each side of adjacent rails at the joint over the flanges of the angle-bars and rails, 25 clamping the flanges of the angle-bars closely against the corresponding flanges of these rails and tending to push or draw the angle-bars into the hollows and against the crowns of the rails, insuring a tight and snug fit.

Furthermore, the invention consists in a railway-rail joint comprising, with the ordinary angle-bars, two jaws arranged one on each side of adjacent rails at the joint over the flanges of the angle-bars and rails, and a 30 bolt or bolts placed beneath the rails and connecting the jaws, whereby when nuts on the bolts are turned on the webs of the angle-bars will be clamped closely against the corresponding flanges of adjacent rails, the angle-bars 35 will be pushed or drawn into the hollows and against the crowns of the rails, insuring a tight fit, and a supporting-pressure will be exerted.

In the accompanying drawings, forming 45 part of this specification, and in which like letters of reference indicate corresponding parts, I have illustrated two forms of embodiment of my invention.

Figure 1 is a perspective view of a railway-rail joint constructed in accordance with my 50 invention. Fig. 2 is a perspective view of a

railway-rail joint, showing a modified form of my invention; and Fig. 3 is a perspective view of the jaws. Fig. 4 is a sectional view, the section being taken on the line $x-x$ of Fig. 1. 55

In the drawings, A A represent the ends of adjacent rails, and B represents the ordinary angle-bar placed at the joint. There will be a corresponding angle-bar on the opposite side, (not shown,) and, as is well known, the crown 60 and flange of each rail are beveled or slanted convergingly toward the stem. The angle-bar is beveled above to fit under the crown and below to fit upon the flange, and the angle-bar is set in the hollow of the rails with 65 about a quarter of an inch space free between its back and the stem or web of the rail, leaving the outer edge of the flange of the angle-bar projecting over or out beyond the flange of the rail. 70

C C represent my improved jaws, which have a configuration to take upon and hold the flanges of the rails and of the angle-bars, and one of which is to be placed on each side of the rails at their point of juncture over the 75 flanges of the rails and of the angle-bars. The jaws are in their general form inclined downward and outward from each side of the rails and are secured together and pressed upon the rails and angle-plates by means of bolts 80 D, passing through suitable openings in them. It will be obvious that the jaws may have any suitable shape other than that shown. For example, the lower surface of either jaw may be in one plane and the jaw present a flat 85 surface. While I deem the use of bolts preferable for tightening or loosening the jaws to form the clamp or vise it will be obvious that any other suitable means for clamping or opening the jaws will fall within the spirit of 90 my invention, which does not depend upon any specified mode of opening and closing the jaws. By this construction the drawing together of the jaws when in position engaging the angle-bars and rails by tightening the 95 nuts on the bolts will result in pressing the angle-bars firmly inward against the rails, and will also serve to bind the angle-plates and the rails closely together. In addition to this, the tightening has the effect of exerting upward strain on the rail by reason of the inclined face of the jaws or clamps. 100

As the angle-bars become loose from cross-wear on the crown and under the flanges of the same, from movement of the rails lengthwise, from expansion and contraction, from the jar of passing trains, or from other causes, 5 the tightening of the nuts will cause the jaws to come together, forming a clamp, forcing the angle-bars into the hollows of the rails to a tight, firm, and snug fit, and clamping the 10 webs together.

The angle-bars may be secured to the rails by the usual number of bolts, or the tops of the jaws may be extended to bear against the stems or webs of the bars. In this case there 15 may be a bolt at each end of the jaws, serving to secure the angle-bars, and also to keep the jaws from slipping lengthwise. It is well to have each jaw about half the length of an angle-bar.

Having thus fully described my invention, what I claim as new, and desire to secure by Letters Patent, is—

1. The combination, with rails and with angle-bars the outer edges of the flanges of which project over or outward beyond the flange of the rail in use, of a jaw or clamp to be on each 25 side of the rail at the joint in use, holding the

flanges of rail and angle-bar and bearing against the projecting flange of the angle-bar when in position, and means for connecting 30 the jaws, substantially as and for the purpose described.

2. A railway-rail joint comprising with the ordinary angle-bars, having their flanges projecting over the rail, two jaws arranged one 35 on each side of adjacent rails at the joint over the flanges of the angle-bars and rails, the jaws being inclined downward and outward from the rails, and a bolt or bolts placed beneath the rails and connecting the jaws, 40 whereby when the nuts on the bolts are turned down the webs on the angle-bars will be clamped closely against the corresponding webs of adjacent rails, the angle-bars will be pushed or turned into the hollows or crowns 45 of the rails, insuring a tight fit, and a supporting pressure will be exerted, substantially as described.

In testimony whereof I affix my signature in presence of two witnesses.

SOLOMON F. STEVER.
